SURVEYORS' CHAINS AND WIND-IN MAGAZINES THEREFOR

Michel Quenot, Besancon, France, assignor to Etablissements Quenot & Cie, Besancon (Doubs), France
Filed May 25, 1960, Ser. No. 31,752
Claims priority, application France June 8, 1959
7 Claims. (Cl. 33—137)

The present invention has for its object a surveyor's chain and a wind-in magazine for that chain, both of which are designed to facilitate the operator's work and render it more accurate.

To this end, and in accordance with a first characteristic of the invention, the surveyor's chain, which is constituted in the manner well-known per se by a graduated metal tape, comprises, at each end, a rod of circular cross-section which is hinged onto a pin located along the plane of the tape and which is provided, at its free end, with a notch designed to facilitate the placing of the chain-pins, this notch being made at right angles to the hinge axis of the rod. A grip is fitted for swiveling about this rod of circular cross-section, and this arrangement eliminates the drawbacks of conventional chains in which the grip, which is swivel-jointed onto the end of the tape to allow it to be oriented in the most appropriate direction relative to the tape from the point of view of the operator holding it, is itself provided with the notch designed to allow the chain-pins to be placed in position; as a result, when a chain-pin is placed in position, it may not always be exactly perpendicular to the plane of the chain, and the position of such chain-pins may consequently be faulty.

The length of the rod of circular section referred to may be of 10 cm. and centimeter graduation marks are provided on the grip.

The tape of such a chain preferably carries a centimetric form of graduation, with decimetric and metric numerical markings, as well as metric indications every decimeter in order to facilitate reading and avoid mistakes.

The wind-in magazine is characterized by the fact that it consists of two circular cheeks joined together by struts along their periphery and a handle which is so positioned that, when the device is held in the hand of an operator, it hangs down normally along the extension of the arm. The handle is fitted to the extremity of tangential extensions of the cheeks; a further pair of extensions, which are substantially diametrically opposed to the others, together form a kind of lip; a strut joining the ends of these latter extensions of the two cheeks is designed to guide the winding-in and unwinding of the tape in a direction substantially perpendicular to that of the arm of the operator, who carries the device hanging from the end of his arm.

One of the two cheeks is solid while the other is annular; a central drum is mounted for rotation about a pin carried by the solid cheek and is able to rotate within the annular cheek. A spring integral in rotation with the drum rubs against the side of the solid cheek and thus acts as a brake on rotation of the drum and thus prevents sudden, inadvertent unwinding.

A winding-handle designed to allow the surveyor's chain to be wound onto its drum is fixed to the latter's periphery and is pivotably mounted so that, in the operating position, the winding-handle is located on the outside and its crank-pin points outwards, while in the inoperative position the winding-handle points inwards and its crank-pin folds away inside the drum.

The annular cheek is provided with a radial slit, as is also the drum; these two slits are designed to allow the rod and the handle of one of the ends of the surveyor's tape to be introduced into or removed from the inside of

2

the drum when they are placed in alignment; to this end, the drum diameter is adequate to accommodate the rod and its grip.

In the accompanying drawings,

FIG. 1 shows one of the ends of the chain.

FIG. 2 is a front view of the wind-in magazine.

FIG. 3 is a cross-sectional view along the lines III—III in FIG. 2.

FIG. 4 is a similar view to that of FIG. 2, showing the chain in the fully unwound condition prior to removal.

The graduated metal tape 1 consisting the surveyor's chain is provided with clearly legible centimetric graduation marks on one of its faces, together with decimetric numerical indications in addition to metric indications.

15 To this end, FIG. 1 shows, on the inner end of a 20-meter long surveyor's chain, the markings and numerical indications corresponding to 19 m. 80 cm.; a hinge 2 located along the plane of the tape is placed at the next decimeter, and on this hinge, which is carried by a reinforcing copper yoke 3, is mounted the cylindrical rod 4 terminating in a half-cylindrical groove 5 the axis of which is normal to the plane of the tape and located at a distance of 10 centimeters from the hinge axis 2; a grip 6 marked with centimeter graduations is mounted 25 rotatable on the cylindrical rod 4.

The wind-in magazine for this surveyor's chain comprises a cheek 7 consisting of a circular disc, and an annular cheek 8, these two cheeks being joined together by regularly spaced struts 9 along their periphery. A wind-in drum 10 is rotatably mounted on the cheek 7 through the medium of a core-piece 11; its diameter is slightly less than the inner diameter of the annular cheek 8 so that it can rotate within the latter and it features a turned-down brim 12 which projects through the central aperture 35 of the annular cheek 8.

A spring-blade 13 is integral in rotation with the drum 10; it comprises two wings 14 which, through slots 15 provided for the purpose in the side of the drum 10, rub against the inner face of the cheek 7 and so prevent uncontrolled rotation of the drum 10.

The two cheeks 7 and 8 are provided with tangential extensions 16 and 17 onto the ends of which is fixed the armature 18 of a handle 19 which is directed substantially perpendicular to the peripheral extensions 16 and 17, and 45 also in an outward direction so that when the operator carries this wind-in magazine at the end of his arm, holding it by the handle 19, the device hangs normally without exerting any bending force on the operator's hand.

The handle preferably embodies four notches, 21, 22, 50 23 and 24, designed to accommodate the four fingers of the operator's hand, and a flat portion 26 located opposite the groove 21 on which the thumb can be rested.

Two further tangential extensions 27 and 28, diametrically opposed to the handle 19, are integral with the 55 cheeks 7 and 8 respectively and their extremities are joined together by a strut 29.

These extensions form a housing for the outer grip 30 of the surveyor's chain in the wound-in position, as shown by the continuous lines in FIG. 2, and facilitate winding-in and unwinding of the chain in a direction substantially parallel to the handle 19.

This winding operation can be controlled by a folding handle 31, the pin 32 of which can be maintained in two opposed stable positions by means of a spring-blade 33; in these two positions, one, the at rest position, is that in which the handle's crank-pin 34 is lodged inside the drum 10, while the other, for winding-in, is that in which the crank-pin 34 points outwards, perpendicular to the planes of the cheeks 7 and 8.

70 The annular cheek 8 is provided with a radial groove 35 through which may be seen, in FIG. 2, the windings 36 of the tape on the drum 10.

The turned-down brim 12 of the drum is also provided with a notch 37 through which can be seen, in FIG. 2, a number of windings 38 of the tape. When tape has been fully unwound and it is desired to withdraw it from its wind-in magazine, all that is needed is to fetch the two radial notches 35 and 37 opposite each other; if the inner grip 39 is then seized and a pull exerted on it at right angles to the planes of the cheeks 7 and 8, there will be no difficulty in withdrawing the surveyor's chain from its magazine.

To replace the chain in the magazine and wind it in, the operations are carried out in reverse order; having first fetched the radial notches 35 and 37 opposite each other, the grip 39 is inserted and placed in position as shown in FIG. 4; the folding winding-handle 31 is then placed in its operating position, and by then rotating the handle via its crank-pin 34 the tape is wound on in the appropriate direction.

It is to be clearly understood that the embodiment of the invention described above with reference to the accompanying drawings has been given by way of example only and not in a limiting sense, and many detail modifications can be made without departing from the scope of the invention.

What I claim is:

1. A surveyor's chain consisting of a graduated metal tape to each end of which is pivotally attached a rigid grip the free end of which is provided with a transverse groove to accommodate a chain-pin, whereby said grips form an integral part of said chain the mensuration capacity of which, twenty meters say, is caused to be the length included between the axes of said transverse grooves when the chain is stretched taut, in which said tape is provided at each end with a transverse hinge lying in the plane of the tape, and each grip consists of a cylindrical rod adapted to pivot in a plane at right angles to said hinge and a grip proper drilled through longitudinally with a cylindrical bore and slipped over said cylindrical rod about which it is freely rotatable, the free end of said rod protruding through said grip and being provided with said transverse groove at right angles to said hinge, whereby said groove always lies in a plane at right angles to said hinge irrespective of any pivotal motion of said rod about said hinge or rotation of said grip about said rod.

2. A chain as claimed in claim 1, in which the grip proper is of circular cross section and provided over its entire periphery with suitable graduation marks, centimetric ones say, measured from the axis of the hinge about which its rod pivots, the distance between said axis

and the axis of the transverse groove on the free end of said rod being equal to ten units of length for example.

3. A chain as claimed in claim 2, in which the grip proper is T-shaped and comprises to that end, at its free extremity, two radial extensions in line with each other.

4. A wind-in magazine for a surveyor's chain as claimed in claim 3, comprising two parallel cheeks between which is rotatably mounted a winding drum, one of said cheeks having a circular aperture opening into the inside of said drum wherein may be accommodated one of the two grips of said surveyor's chain after the tape has been wound onto the drum, each of said cheeks being provided with a first tangential extension and said extensions being interconnected by a strut and being adapted to accommodate between them the longitudinal part of said T-shaped grip after the tape has been fully coiled into said wind-in magazine and to cause said radial extensions of the grip to abut against said strut, which thereby serves to limit the winding motion of the tape on the drum.

5. A wind-in magazine as claimed in claim 4, in which each of said cheeks is provided with a second tangential extension substantially diametrically opposed to the first extension and in which an inwardly turned handle is carried by the free ends of said second extensions so that it lies substantially parallel to the direction of unwinding of the tape.

6. A surveyor's chain according to claim 4, comprising a radial extension of the drum, which is integral with the latter and which extends above the second wall of the magazine, the winding-handle being pivotally mounted on that extension and being capable of assuming, by pivoting action, a retracted position within the drum and an operative position in which it is unfolded outwards of the drum.

7. A surveyor's chain according to claim 6, comprising a flat spring mounted on the winding-handle and cooperating with the radial extension so as to immobilize the winding-handle in both the retracted position and the operative position.
